UNITED STATES PATENT OFFICE.

ALBERT F. PFIFFNER, OF DUBUQUE, IOWA.

SIGN.

1,184,124.

Specification of Letters Patent. Patented May 23, 1916.

Application filed June 10, 1915. Serial No. 33,891.

To all whom it may concern:

Be it known that I, ALBERT F. PFIFFNER, a citizen of the United States, residing at Dubuque, in the county of Dubuque and State of Iowa, have invented certain new and useful Improvements in Signs, of which the following is a specification.

My invention relates to signs, with special reference to signs having removable and interchangeable letters to be used either out of doors or inside and so fastened that they cannot be readily removed by the wind or picked off by passers by, and my object is to provide a back-ground plate of practically uniform color and to attach to said plate, letters, artistically constructed and so set upon the back-ground plate that the eye of the observer will be attracted especially to the artistic letters and their arrangement.

It consists essentially in providing a back-ground plate, which is preferably made smooth and painted or lithographed in any one color and said plate beveled at its edges.

It further consists in letters painted in highly artistic colors and designs and in attaching the letters to the back-ground and also in securing and locking the letters to the back-ground, that they can easily be put in or taken off and still cannot be blown off by the wind or picked off by mischievous boys.

The details of construction and mode of operations will be fully set out in the following specification when read in connection with the drawings accompanying the same and forming a part hereof in which—

Figure 1. is a perspective view of the sign complete. Fig. 2. is a perspective view with the locking frame unlocked and partly raised and showing a plate to which the letters are attached and one of the means for attaching the plates carrying the letters to the back-ground. Fig. 3. is a sectional view of Fig. 1. Fig. 4. shows a plan view of one side of a plate to which the letters are removably attached. Fig. 5. is the same view as Fig. 4 with one letter attached. Fig. 6. is a plan view of the opposite side of Fig. 5 showing the mode of attaching the letters. Fig. 7. is a perspective front-view of an embossed letter. Fig. 8 is a back view of Fig. 7.

Like characters of reference denote corresponding parts in each of the drawings. Referring to the drawings 2 designates

the back-ground plate having the beveled edges 4 and 5. This back-ground plate is preferably painted in a dark gray or brown color. Along each side are set hooks or lugs 6 to which the plates 8, hereinafter to be described, are removably attached. The attaching plates 8 shown in Figs. 3, 4 and 5 consist of flat pieces, preferably strips of thin metal and of the same color as the back-ground plate, so that when the letters are attached the plates will appear a part of the back-ground and substantially invisible which strips are cut rounding at the ends 12 and provided at each end with an opening 10.

The letter 15 is embossed or painted upon a plate 16 of plain surface and the surface is colored preferably the color of the back-ground and the side edges of the plate 16 are bent down to contact with the attaching plate 8. The ends 18 are bent over as shown in Figs. 6 and 8 and bent so as to clasp the attaching plate 8 and be easily slid thereon. These letters may be each of different design and color so that when assembled they will attract the attention of the passer by. Also since they are formed with a substantial clasp that engages the attaching plate, they will not be blown off by the wind or picked off by mischievous children.

For the purpose of securely locking the plates carrying the letter, there is provided a frame 20 that consists preferably of a channel bar 22 with sufficient depth to just rest upon the top of the hooks or lugs 6 and cover both the lugs and the ends of the attaching plate. This frame 20 is hinged at one end to the back-ground and provided with a catch or lock 25 whereby it is locked to the back-ground plate when closed down. The frame may be bronzed if the back-ground is of a brown color or it may be ornamented in any convenient manner according to the taste of the user.

The manner of assembling and operation of the various parts is substantially as follows: The letters are slid upon the plates by means of the clasps and may be arranged so as no two contiguous letters shall be of the same color or design. Then the plates 8 are brought into engagement with the hooks or lugs 6 and may be set horizontally or at an angle, as desired to produce a given effect. If the letters are large so as to contact with each other then the plate 8 would be invisible. The frame 20 is brought down on the

lugs 6 and over the attaching plates 8 and locked to the base plate by the catch 25.

It will be observed that a sign constructed in this manner with the letters removable and interchangeable and ornamented, will present a very attractive appearance and can be changed daily with the minimum of trouble and further the letters will remain as securely upon the sign as though they were each permanently fastened to the back-ground.

Having now described my invention what I claim is:—

A sign including a back-ground, lugs secured thereto adjacent the edges thereof, at-

taching plates formed with openings to engage the lugs, letters having removable sliding connection with the plates and a frame having hinged connection with the back ground, said frame being in part of hollow formation to overlie and conceal the lugs, and means for securing the frame in fixed relation to the back ground.

In testimony whereof I affix my signature in presence of two witnesses.

ALBERT F. PFIFFNER.
